UNITED STATES PATENT OFFICE.

GEORGE WILLIAM CURTIS, OF PHILADELPHIA, PENNSYLVANIA.

CAR-COUPING.

SPECIFICATION forming part of Letters Patent No. 234,175, dated November 9, 1880.

Application filed March 30, 1880. (No model.)

To all whom it may concern:

Be it known that I, GEORGE W. CURTIS, of Philadelphia, in the county of Philadelphia and State of Pennsylvania, have invented a new and Improved Car-Coupling; and I do hereby declare that the following is a full, clear, and exact description of the same.

My invention is an improvement in the class of car-couplings in which the ordinary closed oval link is employed in connection with a coupling-hook which is pivoted and adapted to slide within a draw-head.

The improvement consists in the construction and arrangement of parts, as hereinafter described and claimed.

In accompanying drawings, forming part of this specification, Figure 1 is a longitudinal section of a draw-head provided with coupling devices according to my invention. Fig. 2 is a plan view, part being broken out. Fig. 3 is a cross-section on line $x x$, Fig. 2.

The draw-head A has a narrow lengthwise slot in its upper side, which extends back from its enlarged head b. The slot allows the coupling-hook B to rise as required, to engage with the link C, or to be disengaged therefrom. Said hook has a straight shank, c, whose rear end, d, is enlarged, as shown. A spring-buffer, D, is arranged to slide in the rear end of the draw-head A, and acts on the hook B, pushing it forward, so that its head projects under the shoulder b, and is thus prevented from rising or becoming accidentally disengaged from the link. The hook has pivot-pins e projecting laterally from its rear end, d, and entering lengthwise slots in the sides of the

draw-head. Other pins, f, are located in front of such pivot-pins e to serve as stops to prevent the hook being raised too high, which they do by coming in contact with the top of 40 the draw-head. The means employed for drawing back and raising the hook B are the crank E and chain F. The crank is arranged horizontally and transversely in bearings on the car G, and projects laterally far enough to allow it to be operated to uncouple cars without requiring the brakeman or other person to enter the space between the cars. The chain F connects the crank with the head of the hook, so that upon rotating the crank the hook will 45 be drawn back until its head is free of the shoulder b of the draw-head A, when it will be raised into the diagonal position shown in Fig. 1, and will be thus supported until a link attached to another car enters the draw-head, 50 and, striking on the part d of the hook, simultaneously depresses and forces back the hook, so that it will resume the horizontal position indicated in full lines, Fig. 1, and completes 55 the coupling. The coupling is thus effected 60 automatically.

What I claim is—

In a car-coupling, the combination, with the draw-head having lateral and vertical slots, and the spring-buffer, of the hook B, having 65 lateral pivot and stop pins, as shown and described, for the purpose specified.

GEORGE WILLIAM CURTIS.
